METHOD OF HEATING FLUIDS

Marion W. Barnes, Chicago, Ill., assignor to Universal Oil Products Company, Chicago, Ill., a corporation of Delaware

Application July 15, 1933, Serial No. 680,571

7 Claims. (Cl. 196—47)

This invention relates to a method of operating a furnace of improved design particularly adapted to the heating of hydrocarbon oils to the high temperatures required for their conversion, and more particularly refers to an improved method of simultaneously subjecting different oils to independently controlled heating conditions in a single furnace structure.

I have previously disclosed an improved type of furnace wherein independent control is obtained over the rate of heat input in different portions of the fluid conduit through which oil is passed and wherein it is subjected to pyrolysis. The present invention embodies another furnace of the same general type but particularly designed for simultaneously heating oils of different characteristics whereby each of the different oils is subjected to independently controlled heating conditions regulated to suit the requirements of the particular oil undergoing treatment.

The importance of the factor of time in the pyrolytic conversion of all types of hydrocarbon oils is now generally recognized. When the object of the cracking process is the production of high yields of motor fuel of high anti-knock value, it is essential with light charging stocks such as straight-run gasoline, naphtha, kerosene, or kerosene distillate, pressure distillate bottoms and the like, to heat the oil to a conversion temperature of the order of 900 to 1100° F., when substantial superatmospheric pressures are employed, and to maintain it at or near the maximum conversion temperature attained for an appreciable predetermined length of time. With higher boiling oils such as heavy crudes or topped crudes, fuel oil, heavy gas oil and the like, it is essential for the best results to quickly bring the oil to the desired conversion temperature, for example, from 850 to 950° F., at substantial superatmospheric pressure, and then to either quickly cool the total conversion products to reduce their temperature to below that at which appreciable further conversion will occur or to quickly separate the heavy residual conversion products from the lower boiling vaporous products and prevent extensive further conversion of the former by direct cooling, pressure reduction or both, in order to prevent extensive coke and gas formation. In the present invention quick heating of heavy oils to the desired temperature is accomplished by passing the same in a single continuous stream through a fluid conduit within the furnace in such a manner that it is subjected to progressively increasing rates of heat input 55 in its path of travel therethrough. Subsequent

cooling of the total products and/or rapid separation of the light and heavy products may be accomplished in subsequent portions of the cracking process not pertinent to the present invention. Heating of the light oils to the desired conversion temperature and maintaining them at the desired conversion temperature for a predetermined time is accomplished in the present invention by passing the same through another fluid conduit within the same furnace structure in such a manner that it is subjected to a progressively decreasing rate of heat input as it passes through the fluid conduit.

In a fluid conduit employing a soaking section wherein a single stream of low boiling oils, heated in the preceding portions of the fluid conduit to a suitable conversion temperature, is maintained under conversion conditions for an appreciable predetermined length of time, an unusually large amount of friction is encountered between the oil and the fluid conduit through which it passes, due to the length of the fluid conduit required to obtain the desired time factor. This necessitates the use of exceptionally high pressure upon the stream of oil entering the fluid conduit in order to insure the desired superatmospheric pressure in the soaking section and at the outlet from the heating coil and not only results in excessive pumping costs and the installation of expensive pumping equipment for operation at the unusually high pressures necessary but also involves additional fire hazard, due to the unnecessarily high pressures employed in that portion of the fluid conduit wherein the oil is brought to the desired conversion temperature. Also, in such cases, that portion of the heating coil employing the highest pressures is also the portion wherein it is desirable to employ the highest rates of heat input since a large amount of sensible heat and nearly all of the latent heat of vaporization as well as a substantial portion of the latent heat of cracking must be imparted to the oil in this portion of the fluid conduit while in the soaking section a relatively small amount of sensible heat, only sufficient, in most cases, to overcome radiation losses, and little, if any, latent heat of vaporization, is required so that much lower rates of heat input may be employed in this portion of the fluid conduit.

In the present invention I not only take advantage of the different heating conditions in different portions of the furnace by passing the light oil first through that portion of the fluid conduit located in a highly heated zone of the furnace and subsequently passing it through a

soaking section comprising that portion of the fluid conduit located in a more mildly heated zone of the furnace, but I also provide for decreasing the friction and pressure drop throughout the entire heating coil by employing parallel flow in the soaking section, since the decreased velocity and consequent decreased rate of heating is not objectionable in this portion of the fluid conduit.

The accompanying diagrammatic drawing illustrates one specific form of furnace embodying the various features of the present invention. Fig. 1 is a sectional side elevation of the furnace, and Fig. 2 is a sectional end elevation of the same structure taken along a plane indicated by the line 2-2 in Fig. 1.

Referring to the drawing, the main furnace structure comprises side walls 1 and 1', a roof 2 and a floor 3. Bridge walls 4 and 4' divide the interior of the furnace into separate combustion zones 5 and 6 and a fluid heating zone 7.

Combustion zones 5 and 6 are independently supplied with fuel for combustion through similar firing tunnels 8. Any desired form of fuel such as gas, oil or pulverized solid fuel being supplied by means of burners of any suitable form (not shown) through firing compartments 9 of the tunnels, together with an atomizing medium such as steam and/or a portion of the air required for combustion. Additional air is supplied to the combustion zones through compartments 10 of the firing tunnels, regulated by suitable dampers 11. Combustion of the fuel occurs in zones 5 and 6 of the furnace, each zone being maintained under independently controlled temperature conditions by control of the firing in each zone. The materials undergoing combustion give up heat to the refractory walls of the furnace and to the oil passing through the fluid conduits located within the combustion zones, as will be later more fully described, and the heated refractory walls in turn re-radiate heat to the fluid conduits. The hot combustion gases pass from combustion zones 5 and 6 over the respective bridge walls 4 and 4' and the commingled gases pass downward through fluid heating zone 7 and out of the furnace through flue 12 to a stack (not shown).

Three separate banks of fluid conduits 13, 14, and 15 each comprising horizontally parallel rows of horizontal tubes 16 are located within fluid heating zone 7 between bridge walls 4 and 4' of the furnace. The tubes in the upper rows comprising bank 15 receive a considerable proportion of radiant heat from the combustion gases and from that portion of the roof 2 immediately above these tubes while the tubes in banks 13 and 14 receive primarily convection heat, although a minor portion of radiant heat may also be imparted to the tubes in banks 13 and 14 and considerable heating is also accomplished in bank 15 by convection. The flow of oil through the rows of tubes in banks 13 and 15 is in a general direction counter-current to the flow of the combustion gases through zone 7 while the flow of oil through the rows of tubes in bank 14 is in a general direction concurrent to the flow of combustion gases through zone 7.

A bank 17 comprising a single horizontal row of horizontal tubes 16 is located adjacent floor 3 of combustion zone 5 and in the case here illustrated this tube bank is depressed somewhat below the outlet from firing tunnels 8 in order that the tubes will not be in the direct path of firing and will not be swept by the gases undergoing combustion, thereby minimizing convection heating in this bank, radiant heating from the combus-

tion gases and hot refractory walls of the furnace being predominant. A similar bank 18 is located adjacent floor 3 in combustion zone 6. This bank also comprises a horizontal row of horizontal tubes 16 and is depressed below the outlet from combustion tunnels 8 for the same reasons already given in connection with bank 17. A bank 19 comprising a horizontal row of horizontal tubes 16 is located adjacent roof 2 of combustion zone 6, the tubes of this bank, in the case illustrated, being parallel to the tubes in floor bank 18. A bank 20 comprising two horizontal parallel rows of horizontal tubes 16 is located adjacent roof 2 of combustion zone 5 and in the case illustrated the tubes of this bank are disposed at right angles to the tubes of bank 17 and parallel to the direction of firing in combustion zone 5. That portion of roof 2 adjacent tube bank 20 is elevated somewhat above the rest of the furnace in order to permit easy access to the headers or return bends 21. This also minimizes the extent to which the furnace gases will sweep the tubes of this bank so that convection heating is minimized and radiant heating is predominant.

Suitable headers or return bends similar to those illustrated at 21 in connection with bank 20 are attached to the ends of tubes 16 in each bank and connect adjacent tubes in each row of the respective banks in series. The solid lines between the tubes indicate the return bends on the near side of the furnace. Those on the far side are not indicated in the drawing.

Tube bank 14 is divided into two similar banks each containing an equal number of tubes and each having the same number of tubes in each horizontal row so that two streams of oil may be passed in parallel through the two similar banks, each stream being subjected to equal heating conditions therein.

Tube bank 20 is also arranged, in the case illustrated, for parallel flow therethrough of two substantially equal streams of oil. One stream of oil flows through half of the exposed row 20' of this bank while the other stream flows through the opposite half of the same row. The two streams then cross at the middle of the furnace, each stream flowing through that portion of the shielded row 20'' adjacent the portion of row 20' through which the other stream is flowing. In this manner both streams are subjected to the heating conditions prevailing on the opposite sides of the furnace, thereby tending toward minimizing unequal heating in the two streams, due to any difference in the firing conditions on opposite sides of the furnace. In this manner the two streams of oil flowing through tube bank 20, as well as the two parallel streams flowing through tube bank 14 are subjected to substantially equal heating conditions.

In the case here illustrated, the heavy or high-boiling oil is treated in that portion of the fluid conduit comprising tube banks 13, 15, 19 and 18 and the flow of oil through the various tube banks is in the order named, as indicated in the drawing by the dotted line 22; the oil entering the bottom row of tube bank 13 and emerging from the radiant floor bank 18 and being subjected during its passage through the fluid conduit to a progressively increasing rate of heating.

The light or low-boiling oil passes, in the case here illustrated, through that portion of the fluid conduit comprising tube banks 17, 20 and 14 in the order given. The course of flow through this portion of the fluid conduit is indicated in the drawing by the dotted line 23, the oil entering

the radiant floor bank 17 and emerging from fluid heating bank 14. The low-boiling oil is subjected during its passage through the fluid conduit to a progressively decreasing rate of heating and tube bank 14 comprises a soaking section wherein the oil may be maintained at or near the maximum temperature attained in the preceding portion of the fluid conduit for a predetermined time.

It will be understood that the present invention is not limited to the specific form of furnace here illustrated nor the particular arrangement of fluid conduits and flow therethrough indicated in the drawing but in its broader aspects embraces any method of simultaneously heating separate streams of relatively low-boiling and relatively high-boiling oils in the same furnace structure whereby each stream is subjected to independently controlled heating conditions and whereby the high-boiling oil is subjected to a progressively increasing rate of heating during its passage through the furnace while the low-boiling oil is subjected to a progressively decreasing rate of heating and is maintained for a predetermined time in the latter stages of the fluid conduit through which it passes at a temperature near the maximum attained in the preceding portions of the heating coil.

I claim as my invention:

1. In a process for heating hydrocarbon oils in a furnace comprising two independently fired combustion and heating zones and a substantially convectively heated zone located between said combustion zones and supplied with combustion gases from both, a plurality of vertically spaced horizontally parallel rows of tubes in said convectively heated zone and rows of tubes adjacent the roof and adjacent the floor of each combustion zone, the improvement which comprises passing a stream of hydrocarbon oil through the lower rows of tubes in said convectively heated zone, then through the tubes adjacent the roof of one combustion zone and finally through the tubes adjacent the floor of the same combustion zone while simultaneously passing a separate stream of lower-boiling hydrocarbon oil first through the tubes adjacent the floor of the other combustion zone, then through the tubes adjacent the roof of the last mentioned combustion zone and finally through the central rows of tubes in the said convectively heated zone.

2. In a process for heating hydrocarbon oils in a furnace comprising two independently fired combustion and heating zones and a substantially convectively heated zone located between said combustion zones and supplied with combustion gases from both, a plurality of vertically spaced horizontally parallel rows of tubes in said convectively heated zone and rows of tubes adjacent the roof and adjacent the floor of each combustion zone, the improvement which comprises passing a stream of hydrocarbon oil through the tubes in the said convectively heated zone which are subjected to the mildest heating conditions therein, then through the tubes in the said convectively heated zone subjected to the most severe heating conditions therein, then through the tubes in one combustion zone subjected to the mildest heating conditions therein and finally through the tubes in the same combustion zone subjected to the most severe heating conditions therein and simultaneously passing a separate stream of lower-boiling hydrocarbon oil first through the tubes in the other combustion zone subjected to the most severe heating conditions therein then through the tubes in the last men-

tioned combustion zone subjected to the mildest heating conditions therein and finally through tubes in the said convectively heated zone subjected to heating conditions intermediate to the most severe and the least severe heating conditions therein. 5

3. In a process for heating hydrocarbon oils in a furnace comprising two independently fired combustion and heating zones and a substantially convectively heated zone located between said combustion zones and through which combustion gases from both flow in a downward direction, a plurality of vertically spaced horizontally parallel rows of tubes in said convectively heated zone and rows of tubes adjacent the roof and adjacent the floor of each combustion zone, the improvement which comprises passing a stream of hydrocarbon oil first through at least the two lowermost rows of tubes in the said convectively heated zone, in a general direction counter-current to the flow of combustion gases therethrough, then through not more than the two uppermost rows of tubes in the convectively heated zone, in the same general direction, then through the tubes adjacent the roof of one combustion zone, in a general direction counter-current to the direction of firing and the direction of flow of the combustion gases, and finally through the tubes adjacent the floor of the same combustion zone, in a general direction concurrent to the direction of firing and the direction of flow of the combustion gases, and simultaneously passing a separate stream of lower-boiling hydrocarbon oil through the tubes adjacent the floor of the other combustion zone, in a general direction countercurrent to the direction of firing and the direction of flow of the combustion gases, then through the tubes adjacent the roof of the last mentioned combustion zone, and finally through the central rows of tubes in the said convectively heated zone in a general direction concurrent to the flow of combustion gases therethrough. 30

4. In the heating of hydrocarbon oils to conversion temperatures, the method which comprises passing a relatively heavy oil first through a section of a furnace wherein it is heated predominantly by convection and then through a section of the furnace wherein it is heated predominantly by radiation and subjecting the same during such flow to a progressively increasing rate of heating, simultaneously passing a lighter oil through a section of said furnace wherein it is heated predominantly by radiation and in a path such that it is subjected therein to a progressively decreasing rate of heating, and then passing the lighter oil through the first mentioned section of the furnace and therein maintaining the same at conversion temperature for a predetermined time. 45 55

5. In the heating of hydrocarbon oils to conversion temperatures, the method which comprises passing a relatively heavy oil first through a convection section and thence through a radiant heat section of a furnace and subjecting the same during such flow to a progressively increasing rate of heating, simultaneously passing a lighter oil through a second radiant heat section in said furnace in a path, such that it is subjected therein to a progressively decreasing rate of heating, then passing the lighter oil through said convection section of the furnace, and passing combustion gases from both said radiant heat sections in indirect heat exchange relation with the oils in the convection section. 60 65 70

6. In the heating of hydrocarbon oils to con- 75

- version temperatures in furnaces of the type having a pair of combustion and radiant heating zones which are independently fired near their lower portions and a substantially convectively heated zone receiving combustion gases from both said combustion zones, the method which comprises passing a relatively heavy oil first through said convectively heated zone and then adjacent the roof and finally adjacent the floor of one of said combustion zones and subjecting the same during such flow to a progressively increasing rate of heating, simultaneously passing a lighter oil first adjacent the floor and then adjacent the roof of the other of said combustion zones and subjecting the same to a progressively decreasing rate of heating during its flow through this zone.
7. In the heating of hydrocarbon oils to conversion temperatures in furnaces of the type having a pair of combustion and radiant heating

zones which are independently fired near their lower portions and a substantially convectively heated zone receiving combustion gases from both said combustion zones, the method which comprises passing a relatively heavy oil first through said convectively heated zone and then adjacent the roof and finally adjacent the floor of one of said combustion zones and subjecting the same during such flow to a progressively increasing rate of heating, simultaneously passing a lighter oil first adjacent the floor and then adjacent the roof of the other of said combustion zones and subjecting the same to a progressively decreasing rate of heating during its flow through this zone, and then passing the lighter oil through said convectively heated zone and therein maintaining the same at conversion temperature for a predetermined time.
